(57) **CLAIM**

The ornamental design for a cutting board, as shown and described.

DESCRIPTION

FIG. 1 is a top perspective view of a cutting board showing my new design;

FIG. 2 is a bottom perspective of the cutting board illustrated in FIG. 1;

FIG. 3 is a left side view of the cutting board illustrated in FIG. 1;

FIG. 4 is a front view of the cutting board illustrated in FIG. 1;

FIG. 5 is a right side view of the cutting board illustrated in FIG. 1;

FIG. 6 is a rear view of the cutting board illustrated in FIG. 1;

FIG. 7 is a top view of the cutting board illustrated in FIG. 1; and,

FIG. 8 is a bottom view of the cutting board illustrated in FIG. 1.

The broken lines shown in the figures depict portions of the cutting board that form no part of the claimed design.

1 Claim, 6 Drawing Sheets
